(57) CLAIM

The ornamental design for a mouth tape, as shown and described.

DESCRIPTION

FIG. 1 is a top front perspective view of a mouth tape, showing my new design;

FIG. 2 is a front elevation view thereof;

FIG. 3 is a rear elevation view thereof;

FIG. 4 is a right-side elevation view thereof, the left-side elevation view being a mirror image thereof;

FIG. 5 is a top plan view thereof;

FIG. 6 is a bottom plan view thereof; and,

FIG. 7 is a top front perspective view of the mouth tape shown in a used condition.

The evenly spaced broken lines showing a user in FIG. 7 depict environmental subject matter and form no part of the claimed design.

The dash-dot-dash broken line in FIG. 7 represents a boundary and forms no part of the claimed design.

The remaining evenly spaced broken lines shown in the drawings depict portions of the mouth tape that form no part of the claimed design.
